UNITED STATES PATENT OFFICE.

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKING RETORT OVEN.

Application filed October 13, 1922. Serial No. 594,359.

This invention comprehends improvements of general utility in the coking retort oven art; and also comprehends certain improvements which involve a development of the well-known cross-regenerative coke oven exemplified in the patent to H. Koppers, No. 818,033, dated April 17, 1906.

The invention has for objects the provision of a coking retort oven that is especially designed for the employment of an extraneously derived special generator gas, such as producer gas, as the heating fuel and having, as important characteristics: The recuperative heating of the air employed in the flues combined with the heating of the fuel gas by a system of cross regenerators, whereby the countercurrent principle of heat conservation is employed in connection with the heating of the air where losses arising from short circuiting are substantially immaterial, but regenerative heat conservation is employed in case of the fuel gas to avoid any such losses from short circuiting; and, as a feature that may be secured by the above mentioned combined recuperative-regenerative system, a flue construction that permits constant flame in all the flues of each heating wall of the battery, without any reversal whatever in the direction of flow of the gases through the flues.

In addition to the general objects recited above, the invention comprehends a novel regenerative-recuperative construction and system of flow therethrough and through the flues, and has for other objects such other improvements or advantages in construction and operation as are found to obtain in the structures and devices hereinafter described or claimed.

In the accompanying drawings, forming a part of this specification, and showing for purposes of exemplification, a preferred form and manner in which the invention may be embodied and practised, but without limiting the claimed invention to such illustrative instance or instances:

Figure 1 is a crosswise composite vertical section through a coke oven battery embodying features above specified and equipped with the improvements of the present invention, the view being taken along the major axes respectively of a coking chamber and a heating wall through a pair of crosswise regenerators beneath the coking chamber, in

planes indicated by the lines C—C and D—C 55 of Figure 2.

Figure 2 is a composite vertical section taken longitudinally through the coke oven battery, in planes indicated by the lines A—A and B—B of Figure 1. 60

Figure 3 is a composite vertical section taken crosswise of the battery and through a recuperator in planes indicated by the lines E—E and E—F of Figure 2.

Figure 4 is a horizontal section through the recuperators and regenerator distributing channel taken in a plane indicated by the line G—G of Figure 2. 65

Figure 5 is a horizontal section through the coking chambers and contiguous heating 70 walls taken in the plane indicated by the line H—H of Figure 2.

In the embodiment illustrated in the drawings, the invention is incorporated in a coke oven battery having provision for being 75 operated with an extraneously derived relatively lean gas as the fuel, in order to conserve the entire supply of the relatively richer and more valuable coke oven gas derived from the coking of the coal in the re-torts or carbonizing chambers of the battery. For convenience, the present description will be confined to the embodiment of the invention in such a "gas oven" battery; the novel features and improvements of the invention 80 may be applied to coke ovens of other types, and, in fact, to the general class of heating structures; consequently, the invention is not confined in scope to the specific use and embodiment herein described as an illustrative example. 85

Referring to the drawings, there are illustrated views of a coke oven battery or plant of the by-product type, having features above specified; said oven battery embodies 90 in its construction a plurality of crosswise elongated heating walls 11, 11 and a plurality of intermediate crosswise elongated vertical coking chambers 12, 12. The heating walls 11 form the side walls of the respective coking chambers 12, as shown more particularly in Fig. 2, and, in the present instance, are directly supported, together with the coking chambers, by the heavy supporting walls 13, 13 which extend crosswise of the battery and are located, as shown in Fig. 2, at a lower level than heating walls 11, 11 and coking chambers 12, 12. These walls 100

5 collectively form the main support for the entire super-structure of the oven battery and are themselves supported upon a flat mat or platform which constitutes the sub-foun-
 10 dation on which the entire battery rests. The coal to be coked is charged into the several coking chambers or ovens through charging holes 14 located in the top 15 of the oven battery and positioned directly above the oven or chambers 12, as shown in Figs. 1 and 2. These charging holes 14 are equipped with the usual removable covers, which are removed during charging of the individual ovens or coking chambers and are placed in position to close the tops of such coking chambers during the entire coking or distilling operation. The gases of distillation pass from the tops of the several coking chambers 12 through gas outlets and 20 thence through ascension pipes (not shown) into the usual gas collecting main which carries the distillation products to the by-product recovery apparatus.

25 Heat for coking the charges of coal in the several ovens or chambers 12 is derived from the heating walls 11, which, as above mentioned, extend crosswise of the battery at the sides of the coking chambers. Referring now more particularly to Figs. 2 and 3, each 30 heating wall 11 is constituted of a plurality of flame or combustion flues 17. The flame flues of each heating wall are, in accordance with the invention, operatively disposed into a single group, that is to say all of the flues 35 of each heating wall operate concurrently as upflow or burning flues, as will be herein-after more fully explained. Consequently, heating is maintained continuously from end to end on both sides of the charges of coal in each coking chamber, without any reversal whatever in the direction of flow in the heating flues.

40 The crosswise regenerators 18 of the battery are located at a lower level than the coking chambers 12 and extend in parallelism between pairs of adjacent supporting walls 13. The regenerators alternate with the recuperators, as shown in Fig. 2. Located in the middle lengthwise vertical plane 50 of the battery is a vertical partition 19, as shown in Fig. 1, which partition extends all the way up from the mat of the battery to the bottom of the overlying coking chamber and from one to the other of the supporting walls 13 at the sides of the regenerators. The regenerators, which are respectively located on opposite sides of the battery, extend inwardly to said partition 19 and are separated thereby, as clearly shown in Fig. 1. 55 This arrangement permits control from opposite sides of the battery of the flow through the regenerators, thereby assisting uniformity of distribution of the flow through the regenerators and flues. Each regenerator 18 is a chamber containing open brick work,

commonly called checker work, and indicated at 20, with a vertical distributing channel 21 at the inside of the regenerator and with upper and lower distributing channels 22 and 23 at the outside of the regenerators. 70 The upper and lower vertical distributing channels 22 and 23 are separated by a horizontal baffle 24 which extends inwardly of the regenerator and terminates at the inner vertical channel 21. When the regenerator 75 is operating for inflow, this arrangement compels the flow entering the port 25 to pass through the lower section of the regenerator and inwardly to the inside vertical channel 21, thence upwardly through said channel 80 21, and forwardly through the upper section of the regenerator to the outside vertical channel 22, from which the flow may be delivered by distributing means hereinafter described to the flame flues. When operating for outflow, the flow passes through the regenerator in reverse direction to that just described. The several regenerators are heated, in alternation, by the hot combustion products that draw off from the flame or 90 combustion flues hereinbefore mentioned and then impart such heat to the medium that they feed into these flame flues.

95 Each flame flue 17 has at its top a port or opening 26 for draft and the passage of combustion products or waste gas from the flames within the flue. These ports 26 open up into horizontal or bus flues 27 located in the heating walls above the flame flues and respectively interconnecting all of the flame flues of 100 their respective heating walls. According to the invention, there is provided in each heating wall a series of vertical outflow channels 28 which alternate with the flame flues 17, as shown in Fig. 1. The outflow channels 28 105 receive the waste gases from the horizontal flues 27 and carry them downwardly through the heating wall to the outflow regenerators and to the outflow passages of the recuperators.

110 Extending horizontally above each regenerator 18 is a pair of horizontal distributing channels 29 and 30. The channels 29 and 30 are respectively adapted to be alternately placed in communication with the upper vertical channels 22 of their corresponding regenerators by ports 31 which may be opened or closed by slide dampers 32 which move along the bottoms of the respective channels 29 and 30. The channels 29 of the respective pairs operate as inflow distributing channels for conveying from inflow regenerators the flow directly to the flame flues of the heating walls. For this purpose each distributing channel 29 is communicably connected with the flame flues of a pair of adjacent heating walls by forked ducts 33 and the arrangement is such that each flame flue is provided with forked duct connections to the channels 29 of a pair of adjacent parallel 115 120 125 130

regenerators, in the manner shown in Fig. 2. The other channels 30 operate, however, as outflow channels for conveying the waste gases from the vertical outflow channels 28 to outflow regenerators. For this purpose, each outflow channel 30 is communicably connected with the vertical channels 28 of a pair of adjacent heating walls by forked ducts 34 and each vertical channel 28 communicates, by such forked ducts, with a pair of outflow channels 30.

The recuperators 35 extend crosswise of the battery and in parallelism between adjacent parallel regenerators, so that the recuperators alternate with the regenerators, as shown in Fig. 2. Each recuperator is constituted of the vertical inflow tubes 36 for conveying the preheated air to the flame flues 17 and the surrounding outflow passages 37, through which the waste gases circulate in countercurrent with the inflowing air to transfer heat to the air before it reaches the combustion flues. The inflow passages 36 of the recuperators communicate at their lower ends with horizontal air distributing channels 38, and the surrounding outflow passages of the recuperators communicate at their lower ends with horizontal outflow channels 39. Preferably the said channels 38 and 39 extend inwardly only to the approximate central longitudinal plane of the battery, as shown in Fig. 3, in order to promote uniformity in distribution of the inflow and outflow through the recuperators. The recuperators are located, as shown in Fig. 3, directly beneath the heating walls 11, and their inflow tubes 36 communicate by ports 40 directly with the flame flues 17 of the heating walls located above the respective recuperators. The vertical outflow channels 28 of the heating walls are connected with the outflow passages 37 of the corresponding recuperator by means of ducts 41. With this construction, each recuperator has its inflow passages connected with the flame flues of a single heating wall and its outflow passages connected with the vertical outflow channels 28 of the same heating wall.

The draft through the ports 26 may be regulated by means of the usual movable dampers or sliding bricks 42, positioned in the ordinary way in the bottoms of the horizontal flues 27 and adapted to be reached by access flues 43 which extend from the top of the horizontal flues 27 in each heating wall to the top 15 of the battery, there being an access flue positioned over each flame or combustion flue of each heating wall.

The operation of the retort oven or battery, when employing a special generator gas, such as ordinary producer gas as the fuel, is as follows: Assuming that the alternate regenerators are operating as inflow fuel gas regenerators P and the intermediate regenerators are operating concurrently as

outflow waste gas regenerators W, the slide dampers 32 will be operated to place the distributing channels 29 in communication with the regenerators P and shut off the outflow channels 30. At the same time the 70 dampers 32 of the waste gas regenerators W are operated to place the outflow channels 30 in communication with such regenerators and to shut off the inflow distributing channels 29. A supply of fuel gas is permitted 75 to flow into the alternate fuel gas regenerators P, and passing through said regenerators, the fuel gas is preheated before being delivered by the distributing channels 29 and forked ducts 33 into the flame flues. In the 80 inflow recuperator tubes 36, inflow of air A is maintained and passing upwardly through such tubes is finally delivered by the ducts 40 to the flame flues to support the combustion of the producer gas that is delivered thereto 85 by the alternate fuel gas regenerators P. The waste gases from all of the flame flues pass into the horizontal flues 27 and are by them delivered to the vertical down flow channels 28. Part of the waste gas from 90 the down flow channels 28 passes into the outflow channels 30 and is by said channels 30 delivered into the waste gas regenerators W. The balance of the waste gas w passes from the vertical channels 28 through the 95 ducts 41 into the surrounding outflow passages 37 of the recuperators and passes through said recuperators in countercurrent to the incoming air, for the purpose of pre-heating the air prior to its delivery to the 100 flame flues.

In the coke oven battery just described, reversal of the flow is required only in respect of the regenerators. This may be accomplished by operating the dampers 32 at 105 the end of each operating period to place the inflow regenerators in communication with the flame flues and the outflow regenerators in communication with the vertical outflow channel 28. The reversal operation 110 is accompanied by a delivery of the supply of producer gas to the inflow regenerators and a cutting off of said supply from the outflow regenerators. At each reversal of 115 the flow, the inflow regenerators become outflow regenerators and concurrently the outflow regenerators become inflow regenerators.

By the invention there has been accomplished the employment of constant flame in 120 every flue of the battery, without any reversal whatever in the direction of flow through the flues and yet with a relatively lean gaseous fuel which requires to be regeneratively heated before being delivered into the 125 flues. Moreover, the recuperator system is employed only in connection with the heating of the air and the fuel gas is preheated entirely by a regenerative system, so that countercurrent between the fuel gas and the 130

waste heat is entirely avoided, thereby eliminating any losses of the fuel gas.

The invention as hereinabove set forth is embodied in a particular form of construction but may be variously embodied within the scope of the claims hereinafter made.

I claim:

1. In a coking retort oven, in combination: a plurality of coking chambers; heating walls contiguous to such cooking chambers and respectively constituted of vertical combustion flues and of vertical outflow channels disposed in alternation with said combustion flues and communicably connected therewith; a regenerative system for delivering fuel gas to the aforesaid combustion flues, said regenerative system comprising a plurality of crosswise regenerators, each having a pair of horizontal channels, one of said channels being communicably connected by duct means with the combustion flues of a pair of adjacent heating walls, and the other of said channels being communicably connected by duct means with the vertical outflow channels of a pair of adjacent heating walls, and means for alternatively effecting communication between one or the other of said channels and its corresponding regenerator; and a recuperative system embodying crosswise recuperators for supplying the air to said combustion flues, said recuperators being disposed in alternation with the aforesaid regenerators, the vertical inflow channels of each recuperator being communicably connected with the combustion flues of a single heating wall, and the outflow passages of each recuperator being communicably connected with the vertical outflow channels of the same heating wall; substantially as specified.

2. In a coking retort oven, in combination: a plurality of coking chambers; heating walls contiguous to such cooking chambers and respectively constituted of vertical combustion flues and of vertical outflow channels disposed in alternation with said combustion flues and communicably connected therewith; a regenerative system for delivering fuel gas to the aforesaid combustion flues, said regenerative system comprising a plurality of regenerators, each having a pair of horizontal channels, one of said channels being communicably connected by duct means with the combustion flues of a pair of adjacent heating walls, and the other of said channels being communicably connected by duct means with the vertical outflow channels of a pair of adjacent heating walls, and means for alternatively effecting communication between one or the other of said channels and its corresponding regenerator; and a recuperative system embodying recuperators for supplying the air to said combustion flues, said recuperators being disposed in alternation with the aforesaid regenerators, the vertical inflow channels of each recuperator being communicably connected with the combustion flues of a single heating wall, and the outflow passages of each recuperator being communicably connected with the vertical outflow channels of the same heating wall; substantially as specified.

3. In a coking retort oven, in combination: a plurality of coking chambers; heating walls contiguous to such cooking chambers and respectively constituted of vertical combustion flues and of vertical outflow channels disposed in alternation with said combustion flues and communicably connected therewith; a regenerative system for delivering fuel gas to the aforesaid combustion flues, said regenerative system comprising a plurality of regenerators, each having a pair of horizontal channels, one of said channels being communicably connected by duct means with the combustion flues of a pair of adjacent heating walls, and the other of said channels being communicably connected by duct means with the vertical outflow channels of the same heating wall; substantially as specified.

3. In a coking retort oven, in combination: 75 a plurality of coking chambers; heating walls contiguous to such cooking chambers and respectively constituted of vertical combustion flues and of vertical outflow channels disposed in alternation with said combustion flues and communicably connected therewith; a regenerative system for delivering fuel gas to the aforesaid combustion flues, said regenerative system comprising a plurality of regenerators, each having 80 a pair of horizontal channels, one of said channels being communicably connected by duct means with the combustion flues of a pair of adjacent heating walls, and the other of said channels being communicably connected by duct means with the vertical outflow channels of a pair of adjacent heating walls, and means for alternatively effecting communication between one or the other of 85 said channels and its corresponding regenerator; and a recuperative system embodying recuperators for supplying the air to said combustion flues, the vertical inflow channels of each recuperator being communicably connected with the combustion flues of a single heating wall, and the outflow passages of each recuperator being communicably connected with the vertical outflow channels of the same heating wall; substantially 90 as specified.

4. In a coking retort oven, in combination: a plurality of coking chambers; heating walls contiguous to such cooking chambers and respectively constituted of vertical combustion flues and of vertical outflow channels disposed in alternation with said combustion flues and communicably connected therewith; a regenerative system for delivering fuel gas to the aforesaid combustion flues, said regenerative system comprising inflow and outflow regenerators, the inflow regenerators being communicably connected with the combustion flues, and the outflow regenerators being communicably connected with the vertical outflow channels; and a recuperative system embodying recuperators for supplying the air to said combustion flues, the vertical inflow channels of the recuperators being communicably connected with the combustion flues and the outflow passages of the recuperators being communicably connected with the vertical outflow channels; substantially as specified.

5. In a coking retort oven having coking chambers, and contiguous vertically flued 130

- heating walls, the improvement characterized by means for producing concurrently in each flue of each heating wall constant flame by the combustion of an extraneously derived 5 fuel gas, said means comprising a crosswise regenerative system for supplying to the flues the fuel gas and a crosswise recuperative system for supplying to the flues the air, the regenerative system including regenerators communicably connected with the flue outlets, the recuperative system being provided with outflow passages which communicate with the flue outlets and are adapted to conjointly with said last mentioned 10 regenerators receive the waste gases from said flues; substantially as specified.
6. In a coking retort oven having coking chambers, and contiguous flued heating walls, the improvement characterized by 20 means for producing concurrently in each flue of each heating wall constant flame by the combustion of an extraneously derived fuel gas, said means comprising a crosswise regenerative system for supplying to the flues the fuel gas and a crosswise recuperative system for supplying to the flues the air; substantially as specified.
- 15 7. In a coking retort oven having coking chambers, and contiguous flued heating walls, the improvement characterized by means for producing concurrently in each flue of each heating wall constant flame by the combustion of an extraneously derived fuel gas, said means comprising a crosswise regenerative system for supplying to the flues the fuel gas and a crosswise recuperative system for supplying to the flues the air, the regenerative system including regenerators communicably connected with the flue outlets, the recuperative system being provided with outflow passages which communicate with the flue outlets and are adapted to conjointly with said last mentioned regenerators receive the waste gases from said flues; substantially as specified.
- 25 8. In a coking retort oven having coking chambers, and contiguous flued heating walls, the improvement characterized by means for producing concurrently in each flue of each heating wall constant flame by the combustion of an extraneously derived fuel gas, said means comprising a crosswise regenerative system for supplying to the flues the fuel gas and a crosswise recuperative system for supplying to the flues the air; substantially as specified.
- 30 9. In a coking retort oven having coking chambers, and contiguous flued heating walls, the improvement characterized by means for producing concurrently in each flue of each heating wall constant flame by the combustion of an extraneously derived fuel gas, said means comprising a crosswise regenerative system for supplying to the flues the fuel gas and a crosswise recuperative system for supplying to the flues the air; substantially as specified.
- 35 10. In a coking retort oven having coking chambers, and contiguous flued heating walls, the improvement characterized by means for producing concurrently in each flue of each heating wall constant flame by the combustion of an extraneously derived fuel gas, said means comprising a crosswise regenerative system for supplying to the flues the fuel gas and a crosswise recuperative system for supplying to the flues the air; substantially as specified.
- 40 11. In a coking retort oven having coking chambers, and contiguous flued heating walls, means for producing concurrently in each flue of each heating wall a coking heat, said means comprising a crosswise regenerative system for supplying fuel gas to the flues and a crosswise recuperative system for supplying air to the flues; substantially as specified.
- 45 12. In a coking retort oven having coking chambers, and contiguous flued heating walls, means for producing concurrently in each flue of each heating wall a coking heat, said means comprising a crosswise regenerative system for supplying fuel gas to the flues and a crosswise recuperative system for supplying air to the flues; substantially as specified.
- 50 8. In a coking retort oven having coking

chambers, and contiguous vertically flued heating walls, the improvement characterized by means for producing concurrently in each flue of each heating wall constant flame by the combustion of an extraneously derived fuel gas, said means comprising a crosswise regenerative system for supplying to the flues the fuel gas and a crosswise recuperative system for supplying to the flues the air; substantially as specified.

9. In a coking retort oven having coking chambers, and contiguous vertically flued heating walls, the improvement characterized by means for producing concurrently in each flue of each heating wall constant flame by the combustion of an extraneously derived fuel gas, said means comprising a crosswise regenerative system for supplying to the flues the fuel gas and a crosswise recuperative system for supplying to the flues the air; substantially as specified.

10. In a coking retort oven having coking chambers, and contiguous vertically flued heating walls, the improvement characterized by means for producing concurrently in each flue of each heating wall constant flame by the combustion of an extraneously derived fuel gas, said means comprising a crosswise regenerative system for supplying to the flues the fuel gas and a crosswise recuperative system for supplying to the flues the air; substantially as specified.

11. In a coking retort oven having coking chambers, and contiguous vertically flued heating walls, means for producing concurrently in each flue of each heating wall a coking heat, said means comprising a crosswise regenerative system for supplying fuel gas to the flues and a crosswise recuperative system for supplying air to the flues; substantially as specified.

12. In a coking retort oven having coking chambers, and contiguous vertically flued heating walls, means for producing concurrently in each flue of each heating wall a coking heat, said means comprising a crosswise regenerative system for supplying fuel gas to the flues and a crosswise recuperative system for supplying air to the flues; substantially as specified.

In testimony whereof I have hereunto set my hand.

JOSEPH VAN ACKEREN.
